S. S. ALLWILL

CARBURETOR

Filed Sept. 8, 1926

FIG.1.

FIG.2.

FIG.3.

FIG.4.

Inventor:

Stephen Seymour Allwill

By F. A. Hinckle
Attorney.

UNITED STATES PATENT OFFICE.

STEPHEN SEYMOUR ALLWILL, OF AUCKLAND, NEW ZEALAND.

CARBURETOR.

Application filed September 8, 1926, Serial No. 134,244, and in New Zealand August 7, 1926.

This invention relates to carburetors for internal combustion engines and more particularly the engines used in connection with motor vehicles.

Its object is to provide for a special feed control in which the use of a vacuum tank is eliminated, and also to provide for the supply of fuel to the mixing chamber being cut off should a back fire occur in the explosion of the charge, through any cause.

The invention consists in a carburetor made up of two main parts, as in ordinary carburetors, viz, a fuel holding chamber, and a mixing chamber into which the fuel is

sprayed and mixed with the air to pass into the engine intake, and which fuel chamber is kept supplied with fuel by direct suction from the engine, and which mixing chamber is so constructed and fitted that the nozzles and the engine intake, are automatically closed on a back fire taking place and through the back pressure of gases caused by such back fire.

The invention is illustrated in the accompanying drawings and will be herein-after fully described in relation to such drawings.

Figure 1 is a side elevation of the complete carburetor.

Figure 2 is a sectional elevation of the fuel chamber thereof.

Figure 3 is a sectional elevation of the mixing chamber, the section being taken on the line 3-3 of Figure 1.

Figure 4 is a sectional plan thereof on the line 4-4 of Figure 1.

In carrying out the invention, the fuel chamber A and the mixing chamber B may for convenience be assembled together as in ordinary carburetor construction and assembly. The said chamber A is connected with the fuel supply through a pipe C entering at the top and the mouth of which is fitted with any approved form of float controlled valve C' which acts to prevent any overflowing of the chamber. The connection D to the mixing chamber B extends from the bottom of the fuel chamber and passes

upward into the mixing chamber. The valve C' must be considered as a float controlled check valve since it merely acts to prevent flooding when the fuel supply tank is located above the chamber A. The chamber A is not open to the atmosphere and the valve C' acts to close the supply of fuel when the desired level is reached. As soon as the fuel level in chamber A drops, the valve C' opens, since a partial vacuum is created which will result in fuel running into the chamber from the fuel tank, due to the pressure of the atmosphere on the fuel in the fuel tank.

There is, of course, air in the top of the chamber A which is entrapped therein at approximately atmospheric pressure, which will ensure a flow of fuel through the openings E' and F when the suction effect of the piston creates a partial vacuum in the mixing chamber. To replenish the fuel in the float chamber the parts of the check valve, that is the valve and the float, are so proportioned that the buoyancy of the float will be just great enough to overcome the pressure of the head of fuel on the valve to close the valve when the chamber A is filled to a level with the opening in the inlet member of the mixing chamber.

The fuel is adapted to be drawn from the chamber A by the engine suction and then through the partial vacuum created in the chamber to have the supply in such chamber replenished from the main fuel tank, into which air is allowed to enter to provide the pressure necessary to cause the fuel to flow to the carburetor. This system of feed therefore dispenses with the vacuum tank usually employed with vacuum feed systems and makes the fuel chamber of the carburetor act as its own vacuum tank.

The mixing chamber in this invention is made of vertical cylindrical form, into the bottom of which the fuel is led from the pipe D into an upwardly projecting thimble like fitting or fuel inlet chamber E having in the top end thereof a series of holes E', through which the fuel is designed to

be sprayed. Over this thimble a cap F is fitted closely, but loosely enough, so that it may revolve and the cap top is formed with a number of holes F', in size, number and 5 position corresponding to the holes E', so that they may register therewith, or so that the cap may be turned to close off the holes E'. In the normal position of the cap the holes E' and F' register, and thus provide 10 for a number of fuel jets being drawn upward into the chamber on each suction stroke of the engine. For turning the cap F, a spindle f is affixed to its top and extends out through a gland b in the top of the chamber B. This spindle may be controlled from the car dash by Bowden wire or like connection f' in a well known way.

The air inlet pipe G leads into one side of the chamber and the mixture outlet H from 20 the other side so that the air passes round and over the said cap F in its passage to the engine intake, to thus mingle with the fuel jets and form the explosive mixture.

A cylindrical sleeve J is provided to fit 25 neatly within the chamber cylinder, and such sleeve is formed with ports J'-J² therein which are disposed to register with the respective openings of the pipes G and H. The sleeve however is free to rotate so 30 that solid parts of it may be brought to cover these pipe openings to close them.

Fixed to the cap F is a radially extending 35 vane K that in the normal position of the cap when the fuel jets are open, extends across the space between the cap and the sleeve J to one side of the opening H into the engine intake. At its outer edge this locks with the sleeve J to provide for the cap and sleeve turning together when 40 one is turned, and such connection is so made that when the cap is in its normal position the ports J' and J² register with the connections G and H.

In the normal working of the engine 45 therefore, the fuel will enter in jets through the holes E' and F' and the air will pass through the mixing chamber to form with the fuel, the explosive mixture. Should a back fire take place in the engine intake, 50 the back pressure thereof will then act on the vane K (which is preferably curved as shown in Figure 4 to increase its effectiveness) forcing it to rotate to carry with it the cap F and sleeve J and thereby to close 55 the fuel inlet and also to close the air passage. Thus any possibility of the fuel supply being ignited is prevented.

The parts may afterwards be returned to 60 their normal working positions by turning the spindle f through the means provided for that purpose.

If desired, an electric heating element M 65 may be disposed within the fuel chamber A for the purpose of heating the fuel to render it more readily volatilizable when

mixed with the air. This provision will allow for low grade fuels being employed for the running of the engine.

I claim:—

1. A carburetor comprising a fuel chamber closed to the atmosphere; a fuel supply pipe associated with the chamber; a float-controlled check valve in said chamber and adapted to check the supply of fuel from the supply pipe when the fuel reaches a predetermined level in the chamber; a mixing chamber for mixing the fuel and air and controlling the flow thereof; and a pipe connecting the fuel chamber with the mixing chamber. 70

2. A carburetor comprising a fuel chamber closed to the atmosphere; a fuel supply pipe associated with the chamber; a float-controlled check valve in said chamber and adapted to check the supply of fuel from the supply pipe when the fuel reaches a predetermined level in the chamber; and a mixing chamber associated with the fuel chamber for mixing the fuel and air and controlling the flow thereof. 75

3. A carburetor for internal combustion engines comprising a mixing chamber having an air inlet and an outlet for the fuel mixture; a fuel inlet member in the chamber having an opening therein for the passage of the fuel; a cap on said inlet member and having an opening therein adapted to register with the opening in the inlet member; a sleeve in said chamber having an inlet and an outlet cooperating with the air inlet and the fuel mixture outlet of the chamber; and means connected to the cap and the sleeve and adapted to actuate said cap and sleeve to place the openings in the cap and inlet member and the inlets and outlets in the mixing chamber and sleeve out of register when a back fire takes place in the engine. 80

4. A carburetor for internal combustion engines comprising a mixing chamber having an air inlet and an outlet for the fuel mixture; a fuel inlet member in the chamber having an opening therein for the passage of the fuel; a cap on said inlet member and having an opening therein adapted to register with the opening in the inlet member; a sleeve in said chamber having an inlet and an outlet cooperating with the air inlet and the fuel mixture outlet of the chamber; and a vane connected to the cap and the sleeve and adapted to actuate said cap and sleeve to place the openings in the cap and inlet member and the inlets and outlets in the mixing chamber and sleeve out of register when a back fire takes place in the engine. 85

5. A carburetor for internal combustion engines comprising a mixing chamber having an inlet and an outlet port and an inlet opening for the fuel; a cap in the chamber and associated with said fuel inlet opening adapted to control the flow of fuel into the 90

chamber; a sleeve in said chamber having ports thereto adapted to register with the inlet and outlet ports in the chamber; and a vane associated with and adapted to rotate said sleeve to place the inlet and outlet ports in the mixing chamber and the ports in the sleeve out of register when a back fire takes place in the engine.

6. A carburetor comprising a fuel chamber closed to the atmosphere; a fuel supply

pipe associated with the chamber; a check valve in said chamber and adapted to check the supply of fuel from the supply pipe when the fuel reaches a predetermined level in the chamber; and a mixing chamber associated with the fuel chamber for mixing the fuel and air and controlling the flow thereof.

In testimony whereof, I affix my signature.

STEPHEN SEYMOUR ALLWELL.
